UNITED STATES PATENT OFFICE.

WEBSTER C. ESTES, OF NEW YORK, N. Y., ASSIGNOR TO E. B. ESTES & SONS, OF NEW YORK, N. Y., A CORPORATION OF MAINE.

DESIGN FOR A PIN-HOLDER.

53,411.

Specification for Design.

Patented June 10, 1919.

Application filed March 13, 1919. Serial No. 282,515. Term of patent 14 years.

To all whom it may concern:

Be it known that I, WEBSTER C. ESTES, a citizen of the United States, residing in the borough of Manhattan, city, county, and State of New York, have invented a new, original, and ornamental Design for a Pin-Holder, of which the following is a specification, reference being had to the accompanying drawing, forming part thereof, in which—

I claim:

The ornamental design for a pin holder as shown.

WEBSTER C. ESTES.
